(57) **CLAIM**

The ornamental design for a multi-adjustable putter, as shown and described.

DESCRIPTION

FIG. 1 is a top, left, front perspective of the multi-adjustable putter.

FIG. 2 is a bottom, left and front perspective view of FIG. 1.

FIG. 3 is a top, right and front perspective view of FIG. 1.

FIG. 4 is a bottom, right and front perspective view of FIG. 1.

FIG. 5 is a top, left and rear perspective view of FIG. 1.

FIG. 6 is a bottom, left and rear perspective view of FIG. 1.

FIG. 7 is a top, right and rear perspective view of FIG. 1.

FIG. 8 is a bottom, right and rear perspective view of FIG. 1.

FIG. 9 is a left side view of FIG. 1.

FIG. 10 is a right side view of FIG. 1.

FIG. 11 is a bottom view of FIG. 1.

FIG. 12 is a top view of FIG. 1.

FIG. 13 is a front view of FIG. 1.

FIG. 14 is a rear view of FIG. 1.

FIG. 15 is an exploded top, right and front perspective view of FIG. 1; and,

FIG. 16 is an exploded, top, front, and left perspective view of FIG. 1.

The broken away sections of the shaft separated and bound by a bracket indicates indeterminate length and forms no part of the claimed design.

1 Claim, 16 Drawing Sheets
